(57) **CLAIM**

The ornamental design for an insulated carrier bag, as shown and described.

DESCRIPTION

FIG. 1 is a front elevation view of a first embodiment of an insulated carrier bag showing the new design;

FIG. 2 is a right side elevation view thereof;

FIG. 3 is a rear elevation view thereof;

FIG. 4 is a left side elevation view thereof;

FIG. 5 is a top plan view thereof;

FIG. 6 is a bottom plan view thereof;

FIG. 7 is a rear elevation view of a second embodiment of an insulated carrier bag;

FIG. 8 is a left side elevation view thereof; and,

FIG. 9 is a right side elevation view.

All views of the first and second embodiments are the same except for the addition of the carabiner, and the first embodiment has a single strap handle extending continuously on the side and the top of the insulated carrier bag while the second embodiment has two separate strap handles on the side and on the top.
